UNITED STATES PATENT OFFICE.

CHARLES E. SCRIBNER, OF CHICAGO, ILLINOIS, ASSIGNOR TO WESTERN ELECTRIC COMPANY, OF CHICAGO, ILLINOIS, A CORPORATION OF ILLINOIS.

COIN-COLLECTOR FOR TELEPHONE PAY-STATIONS.

SPECIFICATION forming part of Letters Patent No. 728,309, dated May 19, 1903.

Application filed July 29, 1901. Serial No. 70,075. (No model.)

To all whom it may concern:

Be it known that I, CHARLES E. SCRIBNER, a citizen of the United States, residing at Chicago, in the county of Cook and State of Illinois, have invented a certain new and useful Improvement in Coin-Collectors for Telephone Pay-Stations, (Case No. 496,) of which the following is a full, clear, concise, and exact description.

- 10 My invention relates to a coin-collector, and more particularly to a toll-box for telephone pay-stations. Its objects are to provide improved distributing mechanism for controlling the disposition of deposited coins
- 15 and an improved coin-chute and associated mechanism which will automatically return to the depositor all coins of less than a given size which may have been deposited in the toll-box by mistake or otherwise.
- 20 A further object is to provide a construction by which all coins deposited in the toll-box while a coin previously deposited is still undisposed of will automatically be returned to the depositor, whereby filling up of the
- 25 chute and clogging of the distributing mechanism are avoided.

I will describe my invention by reference to the accompanying drawings, and the features or combinations which I regard as new

30 will be pointed out in the appended claims.

Figure 1 is a front elevation of the toll-box. Fig. 2 is a similar view with the cover removed, showing the interior mechanism. Fig. 3 is a sectional elevation on line 3 3 of Fig. 2, showing the coin-chute and the mechanism therein for arresting a deposited coin and directing its course. Fig. 4 is a sectional view on line 4 4 of Fig. 2 looking in an opposite direction from the view of Fig. 3

40 and showing another side of the coin-chute with a portion of the coin-controlling mechanism. Fig. 5 is a sectional plan view on line 5 5 of Fig. 2 with the coin-controlling mechanism in position to direct the coin into the cash-box. Fig. 6 is a detail view of the polarized coin-controlling electromagnet, its armature, and associated parts. Fig. 7 is a detail plan view of the armature when tilted to one side, showing how an electrical con-

tact is made when the armature is thrown to one side or the other.

The toll-box of my invention is of the general type shown in the patent to A. M. Bullard, No. 665,874, dated January 15, 1901. In this style of toll-box the deposit of a coin 55 is necessary to transmit a signal to the central office and the coin is arrested in its passage within the box, electromagnetic mechanism being provided, under the control of the central-office operator, for throwing the 60 coin into the cash-box, or, if the desired connection cannot be obtained, for throwing the coin into a return-chute leading to the outside of the toll-box. A polarized electromagnet is provided, the armature of which 65 is normally maintained in a central position, but is adapted to tilt to one side or the other, according to the direction in which electric current flows through the magnet-coils. This tilting armature is connected with simple 70 mechanism whereby its movement in one direction will throw the coin into the cash-box, while a movement in the opposite direction directs the coin into the return-chute. The electrical circuits for this toll-box are illus- 75 trated in the said Bullard patent, together with the means whereby the central-office operator may impress upon the toll-line current of the proper direction to throw the coin-controlling armature to either side, as may 80 be desired.

The improvements of this invention relate particularly to the coin-chute, the coin-controlling mechanism, and the electrical contact device.

Referring first to Figs. 2 and 3, it will be seen that the coin-chute *a* is a narrow slot leading in a zigzag path from the top of the box to the return-cup *b* at the bottom. This slot is formed by a shallow channel or recess 90 in the brass plate *d* or framework supporting the coin-distributing mechanism. The plate *d* is secured to the back of the iron toll-box by screws *d*' *d*'. The outer wall of the coin-chute is formed by the thin metal plate 95 *d*², which is secured to the face of the plate *d*, the recessed portions in the face of the plate *d* forming the coin-channel. It will be

observed that this coin-channel, starting at the top and front of the box, as shown in the upper left-hand corner of Fig. 3, leads diagonally downward in a gentle slope nearly to 5 the back of the box, then turns sharply back and passes diagonally downward toward the front of the box, where it turns in a gradual curve and continues as a return-chute a^2 , which leads first to the rear of the box and 10 then turns sharply again toward the front, terminating in the return-cup b at the bottom.

The central portion of the chute is expanded to form a supplementary channel or by-path a' , opening off the main chute just after 15 it has made its first sharp turn and is leading in a nearly-horizontal direction toward the front. The mouth of this supplementary channel thus forms a gap in the lower wall of the chute, into which coins will ordinarily 20 be shunted, and distributing mechanism, hereinafter to be described, is provided for stopping coins in this channel and controlling their subsequent disposition.

Two stops or pins $e' e^2$ normally project into 25 the supplementary channel in position to arrest a falling coin and support the same between them. Means are provided whereby these pins may be independently withdrawn to release the coin, which, directed by the 30 pin which remains, falls to one side or the other, according to which of the pins has been withdrawn.

Two exit channels or paths for the coin diverge from the supplementary channel at a 35 point just below the stops $e' e^2$, said stops serving to block the mouths of said exits. One path leads to the return-chute a^2 and the other path, directly behind the other, (at the right, as seen in Fig. 3,) leads sidewise out 40 of the chute and into the cash-box. This latter path is made by a hole a^3 , cut in the side wall of the coin-chute, and a deflector-plate a^4 , passing diagonally through the hole to throw the coin sidewise out of the chute.

45 A projection d^3 is left between the hole a^3 and the return-passage a^2 , forming a wall dividing the two exit-channels and adapted to assist in directing a falling coin into either of them.

50 The stops $e' e^2$ are separated so that coins of less than a given size will not be stopped, but will fall through between the stops, and the projection d^3 is positioned so that it will be struck by such undersized coins which 55 fall through between the stops and will serve to direct such coins into the return-chute a^2 . Ordinarily when a coin is deposited it passes down the chute as far as the opening formed by the enlarged portion or supplementary 60 channel a' and then is shunted into this channel, being arrested, however, at the entrance by the pins $e' e^2$. Until the coin is disposed of other coins subsequently deposited will pass over the coin so held, which 65 bridges the gap in the lower wall of the chute, so that such other coins will pass on down through the return-chute and out into the

return-cup. Blocking of the chute or of the distributing mechanism is thus avoided.

Above and on either side of the projection 70 d^3 two holes are cut in the plate d , through which the two stops or pins $e' e^2$ project into the expanded portion or supplementary channel a' of the coin-chute. These two stops $e' e^2$ are mounted upon a centrally-pivoted rocking lever e , which forms the armature of a polarized electromagnet f and is adapted to be tilted to one side or the other, according to the direction of current flowing in the coils of the magnet. When thus tilted, one of the 80 stops $e' e^2$ will be withdrawn from the chute and the other thrust farther in. In Fig. 3 a coin is shown resting upon these two stops. It will be seen that if the stop e' is withdrawn the coin will fall forward into the passage a^2 85 and thence into the return-cup. If, on the other hand, the stop e^2 be withdrawn, the coin will fall rearwardly upon the deflector-plate a^4 , and so will be thrown sidewise out of the chute through the hole a^3 and into the 90 cash-box c .

A pin a^5 is provided near the center of the expanded portion a' of the coin-chute in position to arrest a coin as it falls into the mouth of the expanded chamber a' and to 95 direct the coin rearwardly, so that it will fall between the two projecting pins or stops $e' e^2$. If a coin is already in place between these stops, however, a coin subsequently falling through the chute will strike this coin 100 and bounce over the pin a^5 , passing to the front of the expanded chamber a' and thence down and out through the chute a^2 .

The distance between the pins or lugs $e' e^2$ is just sufficient to prevent the passage between them of a coin of the size which is designed to be used in the toll-box—as, for example, a five-cent piece—but will allow smaller coins, such as dimes or pennies, to pass between them.

110 The armature or rocking lever e is shown most clearly in Figs. 4 and 6, and consists simply of an iron plate pivoted at the top and bottom upon the screws $g' g'$. A flat spring h is mounted upon the upper portion of the 115 plate or framework d and projects down, so that its broad lower edge rests upon a strap k , which is mounted on the face of the pivoted armature-plate e . The central portion of the spring h is preferably cut away, as shown in 120 Fig. 4, and the lower edge thereof is of sufficient width so that it may bear upon the armature on either side of its pivotal axis. It thus tends to keep the armature in the central position, from which it may be tilted to 125 one side or the other by the polarized magnet. The projecting ends of the pole-pieces of the magnet are preferably tapered or bullet-shaped, as shown, and the armature has holes cut therein registering with the pole-pieces, 130 the armature being thus adapted to slip over the pole-pieces when it is attracted, whereby a considerable range of movement is made possible. The magnet is preferably mount-

ed as shown in Fig. 5, with the pole-pieces threaded at their ends and screwed into lugs d^5 d^6 , formed on the plate d , which project through the holes in the armature.

5 The lug or pin e' is stationarily mounted upon the armature e ; but the pin e^2 is pivoted to said armature and carries a platinum contact-point, which is adapted to engage a contact-anvil mounted upon a stationary stud e^3 . This stud carries the contact-anvil and is mounted upon but insulated from the armature e . The pin e^2 carries a right-angled extension or cross-pin, the end whereof is engaged by a very light spring i , mounted upon the face of the armature, which tends to keep the pivoted pin e^2 thrown over toward the pin e' and separated from the stud e^3 , so that the electrical contact controlled thereby is normally broken. When a coin rests between the pins e' e^2 , however, the pin e^2 is wedged over, so that its platinum contact-point strikes the contact-anvil on the stud e^3 and completes the electrical connection. When the pin e^2 is struck by coins which are small enough to fall through the channel without being stopped, the spring-mounting of the pin assists in causing such coins to be thrown forward into the return-chute a^2 rather than rearwardly into the passage a^3 , which is an incidental advantage.

A metallic strap k is mounted upon but insulated from the face of the armature e and extends from the top of the armature to the stud e^3 at the bottom. The flat centralizing spring h does not rest directly upon the armature, but rests instead upon the upper portion of this strap, which is insulated from the armature. The spring h may thus form one terminal of the electrical circuit, and the framework or metallic casing of the toll-box may form the other terminal. Usually the framework would be connected to ground and the spring h would be connected through the coils of the magnet f to one side of the telephone-line. When a coin is deposited in the box, the stop e^2 , which is connected through the contact-points g' g' with the grounded framework of the machine, is brought into contact with the stud e^3 , which is connected with the spring h , and so with the line, and the circuit is thus closed from the line to ground.

As shown most clearly in Fig. 7, contact-points e^5 e^6 may be mounted upon the armature e in position to engage the spring h when the armature is tilted to one side or the other to complete the circuit independent of the coin. Normally, however, when the armature is in its central position these contact-points are separated from the spring h , since they do not project as far from the surface of the armature as do the projections i' i' at the upper portion of the strap against which the spring h normally rests. The object of making this contact between the spring h and armature e in shunt of the contact controlled by the movable stud e^3 when the armature

is tilted is to prevent the fluttering of the armature when the coin is released.

Having thus described my invention, I claim as new, and desire to secure by Letters Patent, the following:

1. In a coin-collector, the combination with a main coin-chute and two exit-channels leading therefrom, of two stops projecting into said coin-chute, blocking the entrance to the said two exit-channels, respectively, and mechanism for independently withdrawing said stops, whereby the disposition of a deposited coin may be controlled. 80

2. In a coin-collector, the combination with a coin-chute, of two pins e' e^2 projecting into the coin-chute and adapted to support a coin between them, two paths for the coin, one below each of the said pins, and means for 85 alternatively withdrawing either of the pins to direct a coin into either of the paths.

3. In a toll-box, the combination with a main coin-chute, a cash-box and a return-chute, of two exit-channels diverging from the main chute and leading one into the cash-box and the other to the return-chute, two stops projecting into the coin-chute one above each of the exit-channels, adapted to arrest a coin, an electrical contact adapted to be 95 closed by the coin as it is held by said stops, and mechanism for alternatively withdrawing either of said stops to release the coin and direct the same either into the cash-box or into the return-chute, according to the lug 100 which is withdrawn.

4. In a coin-collector, the combination with a main coin-chute and two exit-channels leading therefrom, one leading to a cash-box and the other to a return-cup, of two stops e' e^2 105 projecting into the coin-chute, one at the mouth of each of said exit-channels, mechanism for alternatively withdrawing either of said stops from the chute, to release the coin and direct the same into the corresponding 110 exit-channel, spring-actuated mechanism normally maintaining both of said stops within the chute to arrest a falling coin, an electromagnet operatively associated with the mechanism for withdrawing the stops, 115 and means for energizing said magnet.

5. In a coin-collector, the combination with a coin-chute having two exit-channels for the coin, one leading to a cash-box and the other to a return-cup, of a rocking lever e having 120 two pins or stops e' e^2 projecting into the coin-chute, one above the mouth of each of said exit-channels, said stops being adapted to arrest a falling coin and support the same between them, a pivotal mounting for the 125 rocking lever, whereby the same is adapted to swing to one side or the other to withdraw either of the stops from the coin-chute and so to release the coin and direct the same into either of the exit-channels, a spring normally 130 maintaining the rocking lever in a central position, and a polarized electromagnet operatively associated with said rocking lever, adapted to move the same, whereby the dis-

position of a deposited coin may be electrically controlled.

6. In a coin-collector, the combination with the coin-chute *a*, of a distributing mechanism having two stops *e' e²* projecting into the coin-chute adapted to arrest falling coins of suitable size, mechanism adapted to be actuated by a coin so held, the distance between said stops being sufficient to permit undersized coins to pass through between them, two exit-channels leading from the main chute, one of said exit-channels being positioned to receive all undersized coins which pass through between the stops, the passage of full-sized coins into said exit-channels being normally blocked by one of said stops, and mechanism for withdrawing either of the stops, to release the coin which may be held thereby and direct the same into either of the exit-channels.

7. In a coin-collector, the combination with the coin-chute *a*, of distributing mechanism having stops *e' e²* projecting into the coin-chute in position to arrest a falling coin of suitable size, said stops being sufficiently separated to allow coins of less than a given size to pass through between them, two exit-channels leading from said chute, the entrance to said exit-channels being normally blocked against the passage of coins by said projecting stops, means for independently withdrawing said stops to direct the coin into either of said exits, and a projection *d³* in the coin-chute below said stop, in position to be struck by undersized coins falling between the stops and to direct such undersized coins into a particular one of said exit-channels.

8. In a coin-collector, the combination with a coin-chute *a*, of a coin-distributing mechanism having two stops *e' e²* normally projecting into the coin-chute in position to arrest a suitably-sized coin and support the same, the stops being sufficiently separated to permit undersized coins to fall through between them, mechanism adapted for actuation by a coin held by the stops, two exit-channels leading one into a cash-box and the other to a return-cup, said channels diverging from the main chute at a point immediately underneath the stops, a projection *d³* dividing the mouth of the return-channel from the mouth of the other exit-channel, said projection being located in position to be struck by undersized coins falling through between said stops and to direct such undersized coins into the return-channel, and means for withdrawing said stops from the chute independently, to release a coin held thereby and direct the same either into the return-cup or into the cash-box, as described.

9. In a toll-box, the combination with a main coin-chute, a cash-box and a return-chute, of distributing mechanism adapted to

arrest and hold a deposited coin and control the subsequent disposition thereof, a path 65 being provided around the distributing mechanism controlled by the coin so held, for shunting directly into the return-chute coins subsequently deposited.

10. In a toll-box, the combination with a 70 coin-chute leading through the box to a return-cup, of a by-path or supplementary channel leading from the main chute, into which coins passing down the chute will ordinarily fall, distributing mechanism for stopping a 75 coin in the supplementary channel, and for controlling the subsequent disposition of the coin so stopped, the coin being held in position to block the entrance to the supplementary channel, whereby coins deposited while the 80 first coin is still held undisposed of will pass through and be returned to the depositor.

11. In a toll-box, the combination with a 85 coin-chute leading through the box to a return-cup, of a by-path or supplementary channel having its mouth opening off the main chute and forming a gap in the wall thereof, into which passing coins will ordinarily fall, a stop adapted to arrest a coin at the mouth of the by-path, whereby the gap in the bottom wall of the chute is bridged by the coin so held and coins subsequently deposited will pass over the first coin and so through the chute to the return-cup, mechanism adapted 90 to be actuated by the coin as it is held by said 95 stop, and means for withdrawing the stop to release the coin.

12. In a toll-box, the combination with a 100 coin-chute leading through the box to a return-cup, of a by-path or supplementary channel having its mouth opening off the main chute and forming a gap in the wall thereof into which deposited coins will ordinarily be 105 shunted, two stops projecting into said supplementary channel adapted to arrest a falling coin at the mouth thereof, whereby the gap in the main chute will be bridged by the coin so held, and coins subsequently deposited will pass by the supplementary channel and on through the chute to the return-cup, mechanism 110 adapted to be actuated by the coin so held, two exit-channels diverging from a point underneath said stops, one of said exit-channels being adapted to direct a coin into the return-cup and the other exit-channel leading 115 to the cash-box, and means for independently withdrawing said stops to release the coin held thereby and to direct said coin into either of the exit-channels.

In witness whereof I hereunto subscribe my 120 name this 3d day of June, A. D. 1901.

CHARLES E. SCRIBNER.
